US0D1044213S

(12) **United States Design Patent** (10) **Patent No.:** **US D1,044,213 S**
Chen (45) **Date of Patent:** **** Oct. 1, 2024**

(54) **HAT**

(71) Applicant: **Linfei Chen**, Zhejiang (CN)

(72) Inventor: **Linfei Chen**, Zhejiang (CN)

(**) Term: **15 Years**

(21) Appl. No.: **29/870,071**

(22) Filed: **Jan. 16, 2023**

(51) LOC (14) Cl. **02-03**

(52) U.S. Cl.

USPC **D2/889**

(58) **Field of Classification Search**
